OVEN DOOR

Filed Oct. 15, 1931

UNITED STATES PATENT OFFICE

WILLIAM J. KIRBY, OF SOMERVILLE, NEW JERSEY

OVEN DOOR

Application filed October 15, 1931. Serial No. 568,907.

My present invention relates to door structure and more particularly, to doors adapted for use with gas stoves, for example, with the ovens of such stoves.

5 An important object of the invention is to provide a door having strength and rigidity comparable to that of a cast metal door combined with lightness, and non-conducting quality; also to have the exterior and interior surfaces formed by sheet metal panels that may be separately provided with enamel or other sanitary finish. Preferably the exterior is adapted to be set approximately flush with the front of the stove, as is desirable in those of the cabinet type. Preferably, the door is adapted to be hinged along the bottom edge and provided with stops for holding it at horizontal, in which position the smooth, flat interior surface is exposed 10 upward like a shelf. Preferably, the panels are secured to the frame by tension members utilizing the spring quality of the panels to hold them against adjacent thrust surfaces on the frame; and preferably each tension 15 member extends from one panel to the other without engaging the frame.

Other features and advantages will appear upon consideration of the following description and of the drawing, in which

20 Fig. 1 is a perspective view of a door embodying the present invention;

Fig. 2 is a section taken along the line 2—2 of Fig. 1;

Fig. 3 is a view in elevation looking at 25 the inner side of the door, parts being broken away to show the underlying structure;

Figs. 4 and 5 are enlarged detail views, showing one of the fastening devices, in section and in perspective, respectively.

30 In the drawing the device is shown as comprising a main door element which is preferably an integral casting of iron or steel, embodying in skeleton form all the operating parts of a complete door, including the peripheral internally projecting flange or frame member 10, the marginal or stop flange 11, the hinge knuckles 12 and preferably also lugs 13, by which the opening movement of the door is limited. The area within the marginal frame or flange is formed with

suitable bracing elements of relatively small area, which may include a diametric horizontal member 14, vertical member 15 and corner braces as 16, 17. Where the members 14 and 15 are cast integral with the frame, 55 they are preferably widened toward the ends, as at 18, 18, 19, Fig. 3, so as to afford a relatively long and strong base of union with the frame.

The bracing members have their outer faces 60 located in the same plane with the outer surfaces of the peripheral flanges 11, so as to form a flat solid bed for the plane sheet metal panel 20 which forms the outer surface of the door. The panel 20 is preferably inset 65 in the marginal flange 11, as at 21, and preferably the inset is well out toward the margin of said flange 11 so as to leave a relatively narrow framing bead 22.

By this construction the bead holds the 70 panel 20 against slip or twist, in addition to the advantages of the continuous plane exterior surface, as concerns appearance and cleanliness.

The interior panel 23 also of suitably finished enamel, heavy rolled sheet metal, is spaced apart a substantial distance from panel 20 and also from the inner surface of the skeleton member 14, 15, so as to leave a substantial heat insulating air space 24. Preferably, this inner panel 23 is inset flush with the top of the internally projecting frame member 10. The inner panel is bedded on suitably distributed thrust lugs 25, of small area, and having their panel engaging surfaces in substantially the same plane.

While it is obvious that panels 20 and 23 may be clamped against their respective bed surfaces, each by a separate set of securing means such as screws, bolts or the like, an important feature of the invention includes special features of the securing means which I employ. One important feature is that the securing means for the inner panel 23 consists of tension members engaging and tensioning said panel 23 at points adjacent but substantially removed from each of its supporting thrust lugs 25 so that the springiness of panel 23 is available to maintain a tight 90 clamping engagement of the panel against its 95 100

supports, during all expansion and contraction such as naturally results from heating and cooling of the oven. While the periphery of this panel 23 could be supported by recessing the top of 10, to form a support surface similar to that provided at 21 for the periphery of panel 20, I prefer, in the case of panel 23 to support its periphery against thrust by providing it with a marginal inwardly turned flange 24'. This serves to stiffen it and preferably the inner faces of oppositely presented portions of 10 flare outwardly so that the flange 24' may have a wedging engagement with said surface. It results that expansion is permitted without any possibility of lateral displacement of the panel 23.

Another feature of the securing means for panel 23 is that it consists of a tension member which engages the other panel 20, so that the two panels are held by a single set of tension members having no engagement with the casting. The casting is cut away to afford very substantial clearance, as at 26. It results that while most of the spring yield required for firm spring clamping of the panels is afforded by panel 23, the strain of panel 20, though much more positive, nevertheless has a substantial margin of spring yield. The result is that the panel 20 is held flatly and rigidly against the extensive surfaces of its skeletonized bed more firmly and with less spring yield than at the panel 23.

A further feature of the securing means is that the tension members are blind fastened to the inner surface of panel 20, the exposed ends being those that pass through panel 23. A very effective but inexpensive means for the anchorage consists of stamped metal fittings comprising wings 27, which may be spot welded to the inner surface of panel 23, formed with a recessed boss 28, slotted as at 29 and adapted to receive a nut element 30, preferably forming the head of a screw sleeve 31, projecting upward through slot 29 and into which screws a bolt member 32, the head 33 of which engages the outer surface of panel 23. It will be noted that there is ample space between the inner surface of panel 23 and also between the end of screw shank 32 and the inner surface of panel 20, so that there is always ample margin for tightening the screw to apply proper spring tension to panels 20 and 23. The casting member 19 and the outer panel 20 have registering openings 35, 35a and 36, 36a, the former pair being for the shank of a door handle (not shown) and the latter pair for a lug to prevent turning of the handle about its axis. The holes 35, 36 flare outwardly to much larger diameter than the holes 35a, 36a, thereby leaving a substantial margin of the latter free to spring inwardly, when clamped. The lugs 38 at the upper edge of the door are flush with the tops of the inwardly projecting frame member 10, and the inner panel is cut away adjacent

these lugs, the latter forming the cooperating member for a spring latch to hold the door closed.

I claim:

1. A door including a relatively thick rigid metal frame formed to embody in skeleton form the operating essentials of a door, in combination with outer and inner sheet metal panels secured against the outer and inner faces of said frame by transversely extending tension members. 70

2. A door including a relatively thick rigid metal frame formed to embody in skeleton form the operating essentials of a door, in combination with outer and inner sheet metal panels secured against the outer and inner faces of said frame by transversely extending tension members which do not engage the frame. 80

3. A door including a relatively thick rigid metal frame formed to embody in skeleton form the operating essentials of a door, in combination with outer and inner sheet metal panels secured against the outer and inner faces of said frame by transversely extending tension members which do not engage the frame, each tension member including a screw element blind fastened to the inner surfaces of the outer panel. 85

4. A door including a relatively thick rigid metal frame formed to embody in skeleton form the operating essentials of a door, in combination with outer and inner sheet metal panels secured against the outer and inner faces of said frame by transversely extending tension members which do not engage the frame, each tension member including a screw element blind fastened to the inner surfaces of the outer panel and engaging the outer surface of the inner panel. 95

5. A door including a relatively thick rigid metal frame formed to embody in skeleton form the operating essentials of a door, in combination with outer and inner sheet metal panels secured against the outer and inner faces of said frame by transversely extending tension members which do not engage the frame, the support face for the outer panel including relatively large area, substantially plane outer surfaces presented by the skeleton frame. 100

6. A door including a relatively thick rigid metal frame formed to embody in skeleton form the operating essentials of a door, in combination with outer and inner sheet metal panels secured against the outer and inner faces of said frame by transversely extending tension members which do not engage the frame, the support face for the outer panel including relatively large area, substantially plane outer surfaces presented by the skeleton frame and which are surrounded by an outer bead of a height substantially equal to the thickness of the panel. 115

7. A door including a relatively thick rigid

130

metal frame formed to embody in skeleton form the operating essentials of a door, in combination with outer and inner sheet metal panels secured against the outer and inner faces of said frame by transversely extending tension members which do not engage the frame, the support face for the outer panel including relatively large area, substantially plane outer surfaces presented by the skeleton frame, and the support for the inner panel including projections having relatively small area, widely distributed surfaces for supporting said panel in a plane substantially parallel with the outer panel.

8. A door including a relatively thick rigid metal frame formed to embody in skeleton form the operating essentials of a door, in combination with outer and inner sheet metal panels secured against the outer and inner faces of said frame by transversely extending tension members which do not engage the frame, the support face for the outer panel including relatively large area, substantially plane outer surfaces presented by the skeleton frame, and the support for the inner panel including projections having relatively small area, widely distributed surfaces for supporting said panel in a plane substantially parallel with the outer panel and located near but a substantial distance from the screw tension members.

9. A door including a steel casting formed to embody the peripheral portions of a door with bracing members across the corners and from side to side thereof outer and inner sheet metal panels secured against the outer and inner faces of the casting.

10. A door including a steel casting formed to embody the peripheral portions of a door with bracing members across the corners and from side to side thereof outer and inner sheet metal panels secured against the outer and inner faces of the casting, the one panel being inset in and substantially fitting surrounding elements of the frame.

11. A door including a steel casting formed to embody the peripheral portions of a door with bracing members across the corners and from side to side thereof outer and inner sheet metal panels secured against the outer and inner faces of the casting, both panels being inset in and substantially fitting surrounding elements of the frame.

12. A door including a steel casting formed to embody the peripheral portions of a door with bracing members across the corners and from side to side thereof outer and inner sheet metal panels secured against the outer and inner faces of the casting, the securing means including cooperating screw elements whereby the outer and inner panels may be spring tensioned toward each other, with the casting between them.

13. A door including a steel casting formed to embody the peripheral portions of a door

with bracing members across the corners and from side to side thereof outer and inner sheet metal panels secured against the outer and inner faces of the casting, the securing means including means associated with the inner face of the outer panel for blind fastening the same.

14. A door including a steel casting formed to embody the peripheral portions of a door with bracing members across the corners and from side to side thereof outer and inner sheet metal panels secured against the outer and inner faces of the casting, the securing means including a fitting spot welded to the inner surface of the outer panel and provided with a boss having a raised, open slot.

15. A door including a steel casting formed to embody the peripheral portions of a door with bracing members across the corners and from side to side thereof outer and inner sheet metal panels secured against the outer and inner faces of the casting, the securing means including a fitting spot welded to the inner surface of the outer panel and provided with a boss having a raised, open slot and a squared screw member, non-rotatably fitting said boss.

16. A door of the class described including a front panel, a rear panel, a metal frame having a flat marginal portion provided at its outer side with a continuous projection within which the front panel fits and at its inner side with a continuous projection within which the rear panel fits, said frame also including members extending inwardly from the marginal portion to support the front panel and studs extending rearwardly to support the rear panel, and means to secure the panels to the frame including parts connected with the inner face of the front panel and parts cooperating with the rear panel and adapted to cooperate with the parts connected with the inner face of the front panel.

17. A door of the class described including a metal frame having a flat marginal portion provided at its outer side and outer edge with a rib and at its inner side with a flange spaced from its inner edge, said frame also having parts within said marginal portion with their outer sides in the same plane as the outer side of said marginal portion and said parts within said marginal portion having at a plurality of positions inwardly projecting studs

and adjacent openings, a flat front panel engaging the outer side of said marginal portion and fitting against the rib at said outer side, a rear panel engaging said studs and having bent back edge portions engaging the inner sides of said flange and with their edges opposite the part of said marginal portion at the inner side of said flange, said rear panel having openings opposite said openings in said frame, nuts connected with the inner side of said front panel opposite said openings in the frame, and screws passing

through corresponding openings in the rear panel and frame and cooperating with said nuts to hold the front and rear panels on said flange.

18. A door of the class described, comprising a flat front panel, a rear panel, a metal frame having a flat marginal portion provided at its inner side with a flange within the outer edge of which the rear panel fits, said frame also including parts extending inwardly from said marginal portion and supporting the front panel at points in the plane of the front of said marginal portion and the rear panel at points spaced rearwardly from the rear face of said marginal portion a distance substantially equal to the difference between the height of the flange and the thickness of the rear panel, and means to secure the panels to the frame including fastening devices extending through said frame adjacent points where both front and rear panels are supported, said fastening devices being attached to the inner face of the outer panel and passing through the rear panel.

19. A door of the class described including a metal frame having a flat marginal portion provided at its inner side with a flange adjacent its inner edge and having an inclined inner face, said frame also having parts within said marginal portion extending to the plane of the outer side of said marginal portion and rearwardly to a plane just to the front of the plane of the top of said flange, a front panel engaging the front face of said marginal portion and said parts within the space enclosed thereby, a rear panel supported by said parts within the marginal portion of the frame with the face of the panel at the inner side of the door substantially flush with the top of the flange, said rear panel having bent back edge portions to engage the inclined side of said flange, and means connected with the inner side of said front panel and with said rear panel for drawing them together and holding them in position on the frame.

20. A door of the class described including a metal frame having a flat marginal portion provided at its inner side with a flange extending around the same, said frame also having supporting parts within said marginal portion with outer sides in the same plane as the outer side of said marginal portion and with spacers extending to a plane just to the front of the plane of the top of the flange, a front panel engaging the front of the frame, a rear panel engaging the spacers and the inner side of the flange, and fastening devices extending through said frame adjacent said spacers and including screws passing through the rear panel, nuts cooperating with said screws and having square heads and tubular central extensions through which the screws are inserted, and nut-holding clips secured to the inner face of the front panel, each of

said clips including parallel sides to engage opposite sides of the square head of a nut, and overlying portions permitting the passage of the tubular central extension therebetween but preventing removal of the head axially of the nut.

Signed at Somerville, in the county of Somerset and State of New Jersey, this 9th day of October, A. D. 1931.
